(57) **CLAIM**

The ornamental design for a pipe bowl with edge lip gap as shown and described.

DESCRIPTION

FIG. 1 is a perspective view of a pipe bowl with edge lip gap showing my new design;

FIG. 2 is a back view thereof;

FIG. 3 is a left side view thereof;

FIG. 4 is a top view thereof; and,

FIG. 5 is a right side view thereof;

FIG. 6 is a front view thereof;

FIG. 7 is a bottom view thereof;

FIG. 8 is a cutaway view from FIG. 4, taken at 8-8 for clarification of the internal structures visible from the open bowl.

FIG. 9 is another perspective view thereof;

FIG. 10 is a perspective view as shown in FIG. 9, shown in an environmental use with screen inserted; and,

FIG. 11 is a cutaway view from FIG. 10 taken at 11-11, shown in an environmental use with screen inserted.

The broken lines showing the screen are for the purpose of illustrating environmental structure and form no part of the claimed design.
